UNITED STATES PATENT OFFICE

2,456,895

WIRE STRETCHER

Hugo Sattler, Doss, Tex.

Application April 10, 1944, Serial No. 530,382

2 Claims. (Cl. 24—71.1)

1

The present invention relates to new and useful improvements in wire stretchers designed primarily for use in the straightening of sagging strands of fence wire so as to tighten the wire and the invention has for its primary object to provide an attachment for the wire and adapted for engaging the sagging portion thereof and retained in a position on the wire to maintain the wire in a taut position.

More specifically the invention embodies the use of a rigid plate member having hook members adapted for engagement by the sagging portion of the wire and embodying means engageable with the wire for pulling the latter into position for engagement by the respective hook members.

A further object of the invention is to provide a wire stretcher of this character of simple and practical construction, which is strong and durable, relatively inexpensive to manufacture, easy to operate and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which

Figure 1 is a front elevational view.

Figure 2 is a vertical sectional view taken substantially on a line 2—2 of Figure 1, but with the vertical screw and collar therefor shown in elevation, and

Figure 3 is a top plan view.

Referring now to the drawing in detail wherein for the purpose of illustration I have disclosed a preferred embodiment of the invention, the numeral 5 designates a substantially triangular shaped rigid plate member having a plurality of vertically spaced hook members 6 struck from the material thereof. The side edges of the plate, adjacent its upper edges, are formed with in-turned flanges 7 behind which the strand of wire 8 may be pulled for engagement with the respective hooks 6.

A triangular shaped holder plate 17 is formed with side flanges 18 forming guides for receiving the lower edges of the plate 5 and a handle 19 projects horizontally from one edge of the plate 17.

The lower end of the plate member 17 terminates in a threaded lug 9 in which a vertical screw 10 is operable, the lower end of the screw having a crank handle 11 formed thereon and the upper end of the screw having a smooth por-

2

tion 12 on which a collar 13 is slidably mounted, the collar being retained on the screw by means of a washer 14 and cotter pin 15.

The lower edge of the collar 13 is formed with a pair of lugs 16 spaced from the screw 10 behind which screw the wire 8 is received for engagement by the lugs 16.

The holder 17 is removably positioned on the lower end of the plate 5 and in the operation of 10 the device and with the holder plate 17 placed in engagement with the plate 5, as shown in Figure 1 of the drawing, the wire 8 is engaged behind the lugs 16 and the collar 13 moved downwardly on the screw 10 so that the sagging portion 15 of the wire, as shown by the dotted line position in Figure 1 of the drawing, can be moved into engagement with the uppermost hook 6. Should it be desired to further tighten the wire 8 the collar 13 is moved into engagement with the threaded portion of the screw 10 so that the 20 rotation of the screw will then cause a downward traveling movement of the collar and thus pull the sagging portion of the strand of wire 8 downwardly for engagement with one of the lower 25 hooks.

Any desired number of the plates 5 may be placed on the wire sufficiently to take up the sagging portion thereof and after the wire has been engaged with a desired hook 6 the holder and 30 screw 10 together with the collar 13 are removed from the plate 5 and the plate 5 retained in engagement with the wire.

It is believed the details of construction, operation and advantages of the device will be readily understood from the foregoing without further detail explanation.

Having thus described the invention, what I claim is:

1. A wire stretcher comprising a rigid plate member having at opposite edges flanges spaced from the remaining part and disposed in substantial alignment, a plurality of hooks on the side of the plate facing said flanges and spaced from one another on a line intermediate the edges of 40 said plate, a holder disposed against the other side of said plate and having at opposite edges guides engaging the edges of said plate, means for engaging a wire extending above the flanges, a second means cooperating with the holder and 45 said plate, a portion guiding said first means axially of said second means and also including threads coacting with the first means.

2. A wire stretcher comprising a rigid triangular plate member having at opposite edges flanges 50 spaced from the remaining part and disposed in

substantial alignment, a plurality of hooks on the side of the plate facing said flanges and spaced from one another on a line intermediate the edges of said plate, a triangular holder disposed against the other side of said plate and having at opposite edges guides engaging the edges of said plate adjacent the apex remote from the flanges, means for engaging a wire extending above the flanges, a second means cooperating with the holder and including a portion guiding said first means axially of said second means and also including threads coacting with the first means.
